ARTICLE RETAINING DEVICE

Fred W. Dittman, Rochester, N. Y., assignor to
 Hickok Manufacturing Company, Inc., Rochester, N. Y., a corporation of New York

Application May 9, 1934, Serial No. 724,807

8 Claims. (Cl. 59—98)

The invention relates to a looped key or like retaining device.

The object of the present invention is to provide for key chains a key ring assembly of a

5 highly ornamental and attractive character constructed and arranged to represent a bull whip and adapted to present an accurate representation of a bull whip looped and having a lash coiled or twisted around a handle, the loop being adapted to receive keys and capable of being readily opened and closed and permit keys to be placed on the key ring assembly and removed therefrom.

10 A further object of the invention is to provide a key or other article retaining device having a receiving loop composed of two sides and a connecting portion, one of the sides of the loop being movable with respect to the other and the movable side having interlocking engagement with the said other side and normally maintained in

20 such interlocking engagement by the resiliency of the material of which the device is constructed.

Another object of the invention is to provide a key ring assembly in the form of a looped bull whip having a portion of the lash spirally coiled around the handle of the bull whip and rigid therewith and the looped portion of the lash arranged to form and present the appearance of a continuation of the fixed portion of the lash when the movable side of the loop is interlocked with

30 the other side of the same.

Another object of the invention is to provide a key ring assembly in the form of a looped bull whip having the interlocking portion of the movable side of the loop arranged to form a guide for placing keys on the key ring assembly when the said movable side of the loop is disengaged from the other side of the loop and the loop is opened to permit keys to be placed on and removed from the same.

40 With these and other objects in view, the invention consists in the construction and novel combination and arrangement of parts herein-after described, illustrated in the accompanying drawing, and set forth in the claims hereto appended, it being understood that various changes in the form, proportion and minor details of construction, within the scope of the claims, may be resorted to without departing from the spirit or sacrificing any of the advantages of the invention.

50 In the drawing:

Fig. 1 is a side elevation of an article retaining device constructed in accordance with this invention, the key ring receiving loop being closed.

55 Fig. 2 is a similar view of the article retaining

device, the loop being open and the terminal engaging portion of the movable side of the loop being arranged to form a guide for placing keys on the assembly.

Fig. 3 is an enlarged edge view of the retaining device, the movable side of the loop being engaged with the slot in the other side of the loop.

Fig. 4 is a similar view showing the opposite edge of the retaining device.

Fig. 5 is an enlarged detail longitudinal sectional view of a portion of the retaining device showing the movable side of the loop in engagement with the slot of the other side of the loop.

In the drawing in which is illustrated the preferred embodiment of the invention, 1 designates a key chain provided at one end with a key ring assembly and having a swivel 2 at the other end for attachment to a belt, garment or the like, but instead of employing a swivel any other suitable means may, of course, be employed for this purpose. The key ring assembly which is illustrated in the form of a looped bull whip may be constructed of precious or semi-precious metal or any other suitable material, and comprises a bar 3 tapered from its inner end and provided at its outer end with a loop 4 forming a continuation of the bar 3 and tapered longitudinally. The loop and the bar represent the handle and a portion of the lash of the bull whip and the said loop which is composed of two sides and a connecting portion has one of the sides formed by the bar 3 and the other side 5 which is movable with respect to the bar 3 is arranged at an angle to the same.

35 The movable side of the loop is provided with a longitudinally curved laterally deflected terminal engaging portion 6 forming a bend 7 which receives one side of the bar when the key receiving loop 4 is closed.

40 When the loop 4 is closed the curved terminal engaging portion 6 extends along the bar 3 and is engaged in a slot 8 thereof. The bar is widened or laterally enlarged at the slot and the curved end 6 extends through the slot from one face of the enlarged portion 9 of the bar 3 to the opposite face thereof to a point adjacent a fixed spirally disposed member 10 extending around the inner or handle portion of the bar 3 and simulating or representing the twisted terminal portion of the lash of the bull whip and which spiral member 10, in any event, provides for a firm grip upon the handle portion of the bar. The end of the curved engaging portion 6 of the movable side of the loop when in the slot is 45 50 55

cated contiguous to one end of the fixed spirally coiled member 10 so that the movable side of the loop and the fixed member present the appearance of the lash portion of the bull whip coiled 5 around the inner or handle portion of the bar 3.

The resiliency of the metal of which the retaining device is constructed maintains the curved terminal portion 6 of the movable side of the loop firmly in engagement with the slot 8 of the bar 3 10 and when the loop is opened by disengaging the end 6 of the movable side 5 of the loop from the slot the said end 6 is carried by the resiliency of the material to the opposite face of the slotted portion of the bar 3 in engagement with the latter and is arranged at an angle to the same and forms a flaring mouth or entrance to the loop 15 providing a guide for enabling keys to be readily placed in the loop of the retaining device.

When the sides of the retaining loop are compressed the terminal engaging portion 6 of the movable side of the loop may be readily sprung into and out of engagement with the slot.

The bar 3 is provided at its inner end with an angularly disposed portion 11 having an opening 12 and forming an ornamental eye into which is linked a ring 13 of the key chain.

What is claimed is:

1. A key ring assembly for key chains comprising a bar provided at one end with means for connecting it to a key chain and having a loop at the other end composed of two sides and an outer connecting portion, the bar forming one of the sides of the loop and the other side of the loop being curved inwardly toward and beyond and movable with respect to the bar portion of the loop and having a terminal longitudinally curved laterally deflected engaging portion extending along one side of the bar and engaged with the same to lock the loop in closed position and adapted to extend along the opposite side of the bar and arranged at an angle thereto to form a guide for the passage of keys into the loop when the loop is unlocked, said bar being laterally enlarged adjacent the engaging end of the movable side of the loop and having an opening spaced from the loop and receiving the said engaging end to lock the loop.

2. A key ring assembly for key chains comprising a relatively long stiff bar provided at one end with means for connecting it to a key chain and intermediate its ends having an opening and having a loop at the other end composed of two sides and an outer connecting portion, the bar forming one of the sides of the loop and the other side of the loop being curved inwardly and crossing the bar portion of the loop in contact therewith and in spaced relation to said opening and movable with respect to the bar portion of the loop and having a terminal longitudinally curved laterally deflected portion extending along one side of the bar toward said opening and loop into said opening to lock the loop in closed position and extending along the opposite side of the bar and arranged at an angle thereto to form a guide for keys when the loop is open or unlocked.

3. A looped retaining device comprising a relatively stiff bar provided with an opening and forming one side of the loop of the retaining device, the opposite side of the loop being extended across the bar from one side thereof to the opposite side of the same and abutting the bar in spaced relation to said opening with the terminal portion of the said opposite side of the loop extending from said abutting engagement between the loop portions and curved inwardly toward

the bar and extending into the opening in the bar to retain the loop detachably closed.

4. A device comprising a bar having an opening intermediate of its ends and a loop formation at one end of the bar, one portion of the bar beyond the opening therein forming one side of the loop and the free end of the opposite side of the loop being laterally deflected and contacting the first mentioned side of the loop in spaced relation to the said opening and having a deflected terminal portion projecting into the said opening to retain the loop closed until the said terminal portion is manually displaced from the opening.

5. A looped retaining device comprising a bar provided with an opening intermediate its ends and beyond the opening forming one side of the loop of the retaining device and the opposite side of the loop being curved and at one portion contacting with and crossing the bar portion of the loop outwardly of the bar beyond said opening and at its terminal end being reversely curved inwardly toward the bar and disposed longitudinally of the latter and having its free extremity removably inserted in said opening in the bar to lock the loop.

6. A looped retaining device comprising a bar provided with an opening and beyond the opening forming one side of the loop of the retaining device and the opposite side of the loop contacting with and crossing the bar of the loop in spaced relation to said opening and being laterally deflected toward the bar and extending in a direction longitudinally of the bar and having the free end of the laterally deflected portion extending inwardly in contacting relation with the bar and removably insertable in said opening.

7. A looped retaining device comprising a tapering bar having an opening intermediate its ends and having its end of greater diameter arranged to provide a handle portion and at the smaller end of the bar having a loop composed of two sides and an outer connecting portion, a portion of the bar forming one of the sides of the loop and the other side of the loop being curved inwardly toward and beyond and movable with respect to the bar portion of the loop and at its outer end deflected laterally and curved with said curved portion extending longitudinally of the bar and its extremity having detachable engagement in said opening, said curved portion and the said extremity thereof when unfastened with relation to said opening springing to the opposite side of the bar and engaging the latter to provide a yieldably opening guide for the insertion of an article into the loop.

8. A looped retaining device comprising a tapering bar having an opening intermediate its ends and having its end of greater diameter arranged to provide a handle portion and at the smaller end of the bar having a loop composed of two sides and an outer connecting portion, a portion of the bar forming one of the sides of the loop and the other side of the loop being curved inwardly toward and beyond and movable with respect to the bar portion of the loop and at its outer end deflected laterally and curved with said curved portion extending longitudinally of the bar and its extremity having detachable engagement in said opening, said curved portion and the said extremity thereof when unfastened with relation to said opening springing to the opposite side of the bar and engaging the latter to provide a yieldably opening guide for the insertion of an article into the loop, and a twisted coiled member on the handle portion extending

substantially throughout the length of the latter and at its inner end terminating at said opening of the bar to thereby permit said twisted coiled member to assume a continuation of a lashed 5 formation of the smaller end of the bar extended as if wrapped around the handle portion of the

device when the free end of the movable side of the loop is disposed in said opening, the twisted coiled member providing a roughness for the handle portion of the device to effect a firm grip on the handle portion.
